UNITED STATES PATENT OFFICE.

JAMES E. SHOEMAKER, OF PHILADELPHIA, PENNSYLVANIA.

AUTOMATIC CONTROLLING AND TIMING MECHANISM FOR FULL-FASHIONED-HOSIERY MACHINES.

Application filed July 16, 1923. Serial No. 651,705.

In full-fashioned hosiery machines as now constructed and operated difficulty arises in properly controlling and timing the different operations, so that the hosiery will conform 5 to definite standards and a uniform number of courses will be made in the different operations such as, for example, in the making of welt, the garter top, the narrowing, the splicing and the other usual operations in a hosiery machine of this type.

With the foregoing in view, my present invention comprehends a novel method of and apparatus for automatically controlling and timing the various operations involved in the 15 making of full-fashioned hosiery.

It further comprehends a novel method of and apparatus for electrically controlling and timing the various operations involved in the making of full-fashioned hosiery.

Many other novel features of construction and advantage too numerous at this point to specifically mention will hereinafter more 20 fully appear in the detailed description of the invention and the appended claims.

For the purpose of illustrating my invention, I have shown in the accompanying drawings embodiments thereof which are at present preferred by me, since these embodiments will be found in practice to give satisfactory 25 and reliable results. It is, however, to be understood that the various instrumentalities of which my invention consists can be variously arranged and organized and that my invention is not limited to the precise arrangement and organization of these instrumentalities as herein shown and described.

It should also be understood that any form of current, polyphase, alternating or direct current, may be used for carrying out my 30 new method of automatically controlling knitting machines.

Figure 1 represents, in front elevation, a portion of a full-fashioned hosiery machine in conjunction with which electrically operated controlling and timing mechanism embodying my invention is employed.

Figure 2 represents, in sectional elevation, a portion of the machine showing the brake mechanism for overcoming the momentum of 35 the parts when the motor circuit is open.

Figure 3 represents a section on line 3—3 of Figure 1 showing more particularly the means for operating the timing mechanism.

Figure 4 represents, in rear elevation, the construction seen in Figure 2. 86

Figure 5 represents a section on line 5—5 of Figure 1.

Figure 6 represents a top plan view of the construction seen in Figure 5.

Figure 7 represents a section on line 7—7 88 of Figure 1.

Figure 8 represents a fragmentary section on line 8—8 of Figure 1.

Figure 9 represents a section on line 9—9 89 of Figure 1.

Figure 10 represents a wiring diagram.

Figure 11 represents a section on line 11—11 of Figure 3 showing certain features of the timing mechanism.

Figure 12 represents a section on line 70 12—12 of Figure 11.

Figure 13 represents a section on line 13—13 of Figure 11.

Figure 14 represents a longitudinal section 75 through a part of the control mechanism, taken between the indicator lines 14—14 in Figure 11.

Figure 15 represents a section on line 15—15 of Figure 14.

Figure 16 represents, in perspective and in 80 detached position, an insulating member seen in Figure 15.

Figure 17 represents a longitudinal section through a part of the control mechanism taken between the indicator lines 17—17 of 85 Figure 11.

Figure 18 represents a section on line 18—18 of Figure 17.

Figure 19 represents a section on line 90 19—19 of Figure 17.

Figure 20 represents a sectional view of an insulating ring in detached position.

Figure 21 represents, in perspective and in detached position, a contact member employed. 95

Fig. 22 represents a longitudinal section through a part of the control mechanism taken between the indicator lines 22—22 in Figure 11.

Figure 23 represents a section on line 100 23—23 of Figure 22.

Figure 24 represents a section on line 24—24 of Figure 22.

Figure 25 represents, in perspective and in detached position, an insulating member seen 105 in Figure 24.

Figures 26 and 27 represent, respectively, in section, a portion of Figure 23 showing the relative positions of certain parts at different times.

5 Figure 28 represents, in perspective and in detached position, the contact member seen in Figure 23.

Figure 29 represents a section on line 29—29 of Figure 11.

10 Figure 30 represents a section on line 30—30 of Figure 11.

Figure 31 represents a section on line 31—31 of Figure 11.

15 Figure 32 represents a section on line 32—32 of Figure 11.

Figure 33 represents a section on line 33—33 of Figure 11.

Figure 34 represents a section on line 34—34 of Figure 11.

20 Figure 35 represents a section on line 35—35 of Figure 11.

Figure 36 represents a section on line 36—36 of Figure 33.

25 Figure 37 represents a section on line 37—37 of Figure 32.

Figure 38 represents, in perspective, another embodiment of switch mechanism which may be employed.

30 Figure 39 represents a section on line 39—39 of Figure 38.

Figure 40 represents a section on line 40—40 of Figure 39.

Figure 41 represents a section on line 41—41 of Figure 39.

35 Figure 42 represents, in plan, certain co-operating parts of the contact mechanism seen in Figure 39.

40 Figure 43 represents, in side elevation, a conventional stocking made by a full-fashioned hosiery machine.

Figure 44 represents a section on line 44—44 of Figure 1, of a narrowing control switch. Figure 45 represents a section on line 45—45 of Figure 44. Figure 46 represents a plan view of a portion of the pattern chain. Figure 47 represents, in perspective, the pattern chain and co-operating parts.

Similar numerals of reference indicate corresponding parts.

50 Referring to the drawings.

1 designates a full-fashioned hosiery machine of any conventional type, and since the construction and operation of machines of this type are now well known to those skilled in this art, I have deemed it unnecessary to illustrate and describe the entire hosiery machine, my invention relating more particularly to the controlling and timing mechanism for the different mechanisms which successively carry out the different requisite operations in the making of a stocking.

2 designates an electric motor, see Figure 1, by means of which the machine is driven, said motor being intergeared in the usual manner with a cam shaft 3, which controls

the knitting operation. 4 designates the hand wheel shaft, which is intergeared with the motor shaft to be driven by it.

5 designates the slide rod which controls the starting and stopping of the machine by 70 means of a primary switch 6, the construction and operation of which will now be explained, see more particularly Figures 1, 38, 39 and 40.

The primary switch.

75

The slide rod 5 has connected to it a link 7, the free end of which is connected to an arm 8, fixed to a shaft 9 journalled in the casing of the primary switch 6. The link 7 is connected to a sleeve 10, see Figure 38, to which is connected the inner ends of the springs 11 and 12, the outer ends of such springs being secured to fixed bearings 13 and 14, respectively, so that when the slide rod 5 is moved from its neutral position, it will, when released, automatically return to such neutral position. The shaft 9 has mounted on it a contact carrying arm 15, see Figure 39, on which are mounted the contacts 16 and 17, each of these contacts being mounted in a similar manner, it will be seen from Figure 39 that an insulating sleeve 18 is in threaded engagement with the contact arm 15 and has its end closed by means of a cap nut 19 which forms an abutment for an end of the spring 20, the forward 95 end of which presses against its respective contact such as, for example, 17, so as to move it outwardly.

Each cap nut 19 carries a binding post 21 to each of which is connected a conductor 22 100 which leads to a binding post 23. The casing of the primary switch 6 is provided with an insulating plate 24. The plate 24 carries a contact segment 25 which merges into a segment of insulation 26, the contact segment 25 105 having connected to it a conductor 27, see Figure 40. Beneath the contact segment 25, is a contact segment 28 which merges into an insulating segment 29 and this contact segment 28 has connected with it a conductor 30. The binding post 23, see Figure 39, has connected to it a conductor 31, see Figure 10. The conductor 30, see Figures 1, 10 and 40, is connected with an electro-magnet 32 which controls the main switch 33, so that, when the switch 33 is closed, the circuit is closed through the primary winding 34 of the motor 2. It will be seen that four conductors are employed for the feed line, 35, 36, 37 and 38, respectively, so that, when the switch 33 is 120 closed, the current will pass through the primary winding of the main motor through the lines 35, 36, 37 and 38 and also through the line 40, so that the motor is now in operation to drive the hand wheel shaft 4 and the cam shaft 3, see Figure 1, to actuate the mechanisms driven and controlled thereby.

As soon as the switch 33 closes the circuit, the current flows through the line 41 to a solenoid 42 returning by the line 43, see Fig- 130

ture 10. The solenoid 42 controls the brake mechanism which co-operates with the hand wheel shaft 4 to effect its release when the motor 2 starts, and to set the brake mechanism when the motor 2 stops.

Referring now more particularly to Figures 1, 2, 3, 4 and 10, I will describe the brake mechanism for the hand wheel shaft 4.

10 Brake mechanism for the hand wheel shaft.

The shaft 4 has mounted on it a friction wheel 44 around which passes a friction band 45 one end of which is secured to a fixed point, as at 46, while its opposite end is connected to one end of a link 47, the other end of said link being connected to a bell crank lever 48, suitably fulcrumed and connected with the armature of the solenoid 42, so that, when the armature is energized, the brake 45 will be released, and, when de-energized, it will be set by the spring 49. The hand wheel shaft 4 is provided with a gear 50 which meshes with a gear 51 on the cam shaft 3, see more particularly Figures 3 and 4.

25 The cam shaft 3, see Figure 3, is provided with a sprocket wheel 52 around which passes a sprocket chain 53 which also passes around a sprocket wheel 54 mounted on a shaft 55 journalled in the timer casing 56 of the timing mechanism which latter will now be described.

Timing mechanism.

The shaft 55, see Figure 11, is operatively connected by means of reduction gearing 57, driven from a pinion 58 on said shaft 55, with a shaft 59 journalled in the timer casing 56 to effect the drive of such shaft 59. In practice, the ratio between the shafts 55 and 59 is ten to one for a twelve hundred course stocking, the ratio varying in accordance with the number of courses in the stocking. The shaft 55 is provided with a worm 60, see Figures 11 and 12, which meshes with a worm gear 61 on a shaft 62 journalled in the timer casing 56. This shaft 62 is provided with a worm 63 which meshes with a worm gear 64 mounted on a shaft 65 suitably journalled in the timer casing 56. The arrangement is such that the shaft 55 revolves, relatively to the shaft 65, in the ratio of twelve hundred to one for a twelve hundred course stocking.

The shaft 65 has mounted on it, and insulated from it, a conducting disc 66, see Figures 11, 13 and 14, on the periphery of which a brush 67 rides, said brush being pivotally connected at one end with an arm 68 which is mounted on and insulated from a rod 69 journalled in the timer casing 56. A spring 70 is provided, one end of which is connected to the arm 68, while its opposite end is connected to the brush 67 to retain it in contact at all times with the conducting disc 66. A conductor 71 is connected with the arm 68.

In proximity to the conducting disc 66, a timing disc 72 is mounted on and insulated from the shaft 65, see more particularly Figures 14 and 15. The disc 72 is provided near its periphery with a dove-tailed groove 73 in 70 which are adjustably mounted the insulating members 74, 75, 76, 77 and 78, respectively, each of which is provided with an upwardly extending lug 79, see Figure 16, and with tapered side walls 80 so as to fit in the groove 75 73, one wall of which is formed by a removable ring 81, see Figure 14.

82 designates a brush which is carried by an arm 83 which is mounted on and insulated from the shaft 69, said arm having connected with it one end of a spring 84, the opposite end of which is connected to the brush 82. A conductor 85 is connected to the arm 83.

Referring now to Figures 11 and 30, the conductor 85 is connected to a spring actuated brush 86 pivotally carried by an arm 87 fixed to a supporting rod 88, and adapted to ride on the periphery of a conducting disc 89 having an insulated portion 90. The disc 89 is electrically connected through its hub with a disc 91 on the same shaft 55 but insulated from said shaft. A brush 92, see Figures 11 and 29, rides on the periphery of the disc 91, said brush being spring actuated and pivoted to an arm 93 fixed on the shaft 88. The brush 92 is connected with a conductor 94 connected to a spring pressed brush 95 carried by and insulated from a supporting rod 96. The brush 95 is connected by a conductor 97 with the switch 33 and thereby with the line 35. The line 31 is connected with the spring pressed brush 98 carried by and insulated from the supporting rod 96, said brush 98 being connected by line 99 with the brush 86. The brush 98, see also Figure 32, rides on the periphery of a conducting disc 100 mounted on and insulated from the shaft 59 and having an insulated portion 101. The brush 95 rides on the periphery of a conducting disc 102, see also Figure 31, mounted on and insulated from the shaft 59.

The above described circuits control the starting and stopping of the machine, as will be clearly set forth in the description of the 115 operation.

The fashioning or narrowing.

After the welt of the stocking has been formed, the machine stops and the garter 120 top is formed.

The line 103 leads into a line 115 having a solenoid 116, see Figures 1, 5, 6, 10, 46, and 47, which when energized, draws downwardly a lever 117, which rocks a lever 118 to actuate a pawl 119 to turn a ratchet 120 one tooth, so that the high lug 121 on the pattern chain 122 will pass beyond the trip arm 123. The pawl 124, see Figure 5, operatively connected with the cam 125 to be ac- 130

tuated by it, then actuates the ratchet 120 in the usual manner. When the next high lug 121 comes into the path of the trip 123, the narrowing mechanism is automatically 5 thrown out of action.

The current passes through line 115, see Figure 10, to a spring actuated contact brush 126, carried by and insulated from the shaft 69, thence from said brush to disc 127, being 10 insulated by the rings 128 and 129, respectively, see Figures 22 and 23.

The current will pass through said disc when either one of the conducting members 130, 131 or 132, see Figure 23, comes into contact with the brush 126, the current passing 15 to disc 133 through the hub of said disc, see Figure 22, to brush 134, from brush 134 by line 135 to brush 136 which is mounted on and insulated from the shaft 96 and rides 20 on the periphery of a disc 137, having an insulated portion 138 and a contact 139, see Figures 10 and 35.

When in operation and the contact 139 of the disc 135 engages the brush 136, the current 25 will flow through discs 137, 140, 141, 100 and 102, brush 95, line 97 and line 35.

During the formation of the garter top the narrowing begins and as will be understood by those skilled in this art there are three narrowing operations during the knitting of the 30 stocking and during all of this narrowing the sped of the motor is automatically reduced.

Referring now more particularly to Figures 1 and 44 to 47 inclusive, it will be seen 35 that the pawl 204 is provided which is connected by means of a link 205 with a fixed lever 206, the shaft 207 of which is connected with a contact carrying arm 208 mounted within the casing of the automatic speed 40 reducing switch 209. 210 designates an insulated plate mounted within the switch casing. The contact 211 is in electrical connection with a conductor 212. The insulated plate 210 carries a contact segment 213 with 45 which is adapted to engage the contact 211. A conductor 214 leads from the contact segment 213 and connects with line 103, see Figure 10. The line 212 leading from the movable contact 211 is connected with a magnet 50 215 which in turn is connected by a line 216 with the line 97, see Figure 10. The electromagnet 215 controls the switch 217 in such a manner that on the electromagnet 215 being energized the switch 217 is closed and on being de-energized the switch 217 is opened. 55 The opening of the switch 217 cuts in a portion of the resistance 108 of the secondary winding of the motor 2 and thus reduces the speed of the motor. The main pattern chain 60 is provided with the contact lugs 218 which control the pawl 204 and thereby the automatic speed reducing switch 209.

Referring now more particularly to Figure 10, the line 103 is connected to the switch 65 33 with line 36 and it is also connected with

the line 104 having an electro-magnet 105 which controls the switch 106. The line 104 leads to a spring actuated brush 109 carried by and insulated from the rod 69 and adapted to ride on the periphery of a conducting disc 110, see Figures 10 and 24, mounted on and insulated from the shaft 65. The disc 110 has an annular groove 111 in its periphery in which is circumferentially adjustable an insulated portion 112. The current passes from the disc 110 to the disc 200 through the hubs of said disc thence to the brush 201 and by line 203 to return line 97 and thence to the main switch 33.

Tight and loose stitching.

It is common practice in machines of this type to change from a tight to a loose stitch in the garter top for the purpose of inner stitching the silk leg portion to the cotton welt.

To tighten stitch.

The current flows by line 103 from feed line 36 to solenoid 142 to line 143 to brush 144 to disc 145 to disc 146, to brush 147, from the brush 147 by line 148 to brush 149 of the disc 141, said disc having the insulation ring 150 therein, see Figures 10 and 34. The current, closed by the contact member 153, passes from brush 147 to disc 141, thence to discs 100 and 102, to brush 95, to line 97, to feed line 35, the disc 145 having on its periphery the groove 152 adapted to receive and retain the contact member 153, said groove being formed by the insulated rings 154 and 155, respectively. This may be more clearly seen from Figures 17, 18 and 20.

To loosen stitch.

The current passes by line 103 from feed line 36 to solenoid 156, see Figure 10, to line 157, to brush 158, which, being rigidly held on the insulated shaft 69, and in contact with the disc 159, whose construction is the same as disc 145, the current passes through said disc by way of contact member 160 and the hub of said disc to the disc 161, through said disc to contact brush 162, which is carried by the insulated shaft 69. The current passes from said brush 162 to line 163, to contact brush 164 on the insulated shaft 96, from said brush 164, the current passes through the insulated disc 140, see Figures 10, 11 and 33. The disc 140 has on its periphery the insulated ring 165 fastened thereon together with the contact 166, see Figure 33. The current passes through this contact 166 when it comes into engagement with the brush 164, then to disc 141, 100 and 102, and from disc 102 to brush 95 to line 97 to line 35.

When the stitch is to be tightened, the current passes from line 36 and line 103 to the solenoid 142, which is energized, due to the contact 153 on the disc 145, see Figure 18, en-

gaging the brush 144 which is connected by line 143 with said solenoid 142. The current passes from disc 145 to disc 146 and brush 147, and by line 148 to brush 149, so that when 5 the contact 151, see Figure 34, engages the brush 149, the current passes by discs 100 and 102, brush 95 and line 97 to line 35.

The contact 153 of the disc 145 comes into engagement with the brush 144, four hundred 10 and thirty courses from the beginning of the welt, or after four hundred and thirty revolutions of the drive shaft 55. When the solenoid 142 is energized, see Figures 7 and 8, it draws the arm 167 upwardly, and this arm 15 has a slot 168 therein to receive the pin 169 of the arm 170, which actuates the shaft 171 of the stitch control in the direction indicated by the arrow marked "a" see Figure 8.

172 designates a lever mounted on and 20 hinged to the shaft 171 and having the ratchet teeth 173 on the periphery of the hub 174 of said lever.

175 designates a flat spring fastened to the 25 arm 176 which frictionally holds the lever in the position for tightening the stitch of the leg portion, said stitch being tightened for six hundred and ten courses, which is the length of the leg portion, or 610 revolutions of the drive shaft 55.

30 When the stitch is to be loosened, the contact 160 of the disc 159 comes into engagement with the brush 158, after 1040 revolutions have been made. The solenoid 156 is then energized, see Figures 7 and 8, thus 35 drawing the arm 177 upward, giving motion to the shaft 171 through the pin 178 of the arm 170 extending into the slot 179 of said arm 177, and the shaft 171 is rotated in the direction indicated by the arrow "b" see Figure 8, thereby actuating the lever 172 in a direction to effect the loosening of the stitch.

When the solenoid is energized, the loose stitching will be knit to the end of the stocking, which takes place during one hundred 45 and sixty courses or revolutions of the shaft 55.

I will now describe the entire operation of the controlling and timing operation with reference to the making of a full-fashioned stocking such as seen in Figure 43.

Assuming now that the full-fashioned hosiery machine employing my novel controlling and timing mechanism is ready to begin the making of the stocking, the operator 55 moves the slide rods 5 to the right in the direction of the arrow A seen in Figure 10 thereby closing the circuit through the primary switch 6 and energizing the electro-magnet 32 to close the circuit through the main switch 33. This starts the motor and the 60 making of the welt 185 begins. I will first explain the operation of the primary switch 6. When the slide rod 5 is moved to the right, as before explained, the lever 8 is moved and 65 thereby the contact carrying arm 15 so that

the contacts 16 and 17 are brought into contact with the contacts 25 and 28, respectively. The circuit is closed by the current passing through the feed or lead wire 35, line 27, contact segment 25, contacts 16, wire 22, contact 70 17, contact segment 28, line 30 to electro-magnet 32 and thence to line 36. This energizes the electro-magnet 32 and effects the closing of the main switch 33.

As soon as the slide rod 5 is released by the 75 operator, the lever arm 8 returns to its neutral position. The contacts 16, see Figure 39, have now passed out of engagement with the contact segments 25 but the contact 17 is still in engagement with the contact segment 28. 80

The current now passes from line 36 to electro-magnet 32, to contact segment 28, to contact 17, line 22 to line 31, the brush 98, through line 99 to brush 86, thence through line 85 to brush 83. The wheels 100, 89 and 72 are in 85

multiple with the wheels 102, 91 and 66 so that the current returns by line 97 to line 39. The shaft 55 is connected with the cam shaft 3 to be driven at the same speed and each revolution of the cam shaft 3 and likewise of the 90 shaft 55 produces one course in the stocking.

The shaft 55 revolves ten times to one revolution of the shaft and the shaft 65 revolves once for 1200 revolutions of the shaft 55 assuming of course that a 1200 course stocking 95

is to be produced. The conducting disc or wheel 100 has the insulating member 101, see Figure 32, the disc 89 has the insulation 90, see Figure 30, and the timing disc 72, see Figure 15, has the insulating members 74, 75, 76, 77 and 78. During the formation of the 100

welt, the discs 100, 89, 72 revolve until their brushes register with the respective insulating members of such discs which causes the circuit to be broken, electro-magnet 32 is deenergized and the main switch 33 opened. This 105

opening of the main switch 33 releases the solenoid 42 thereby permitting the spring 49 to draw up on the member 47 and tighten the 110

brake band 45 around the brake drum 44 fixed to the shaft 4. The welt has now been completed and the next step is the formation of the garter top. The operator moves the slide 115

rod 5 in the direction of the arrow a, see Figure 10, as before explained, the circuit being closed in the same manner as that already described and the straight knitting of the garter top begins. This straight knitting continues until the first narrowing operation. 120

Referring now to Figures 22 and 23, it will be seen that the disc 127 has the insulating members 128 and 129 on which rides the brush 126. The disc 127 revolves in the direction of the arrow seen in Figure 23 and as soon as the contact member 130 is brought 125 into engagement with the brush 126, the circuit is closed through the discs 127 and 133. The current comes from the line 97 to brush 95, the disc 102 and the hubs of discs 100, 141, 140 and 137, the periphery of which lat- 130

ter is insulated except by the contact member 139, so that when this contact member 139 is engaged by the brush 136, the current passes through line 135 to disc 133, to disc 127, from disc 127 by line 115 through solenoid 116 and returns by the line 103. The solenoid 116 is now energized thereby drawing down the levers 117 and 118 thereby causing the pawl 119 to co-operate with the 5 ratchet 120, see Figures 5 and 6, and the pattern chain 122 will be advanced one step and the stop lug 121, see Figure 47, will be moved from beneath the trip arm 123 so that the 10 main driving pawl 124 will be permitted to move into operative engagement with the ratchet 120 and the pattern chain 122 will be advanced until the next stop lug 121 of the pattern chain is positioned beneath the trip arm 123 to render the driving pawl 124 15 inoperative, see also Figure 5.

Prior to the beginning of the narrowing operation a pattern lug chain 218 comes into the path of the lever 204 so that the speed of revolution of the motor will be reduced during the narrowing operation, as will be now 20 explained. When a lug 218 raises the lever 204, see Figure 47, the lever 206 of the speed reducing switch will be brought into the position seen in Figure 45 thus opening the circuit and de-energizing the magnet 215, see Figures 10 and 47, thus causing the switch 217 to open. This opening of the switch 217 cuts in a portion of the resistance 108 of the secondary winding 107 of the motor 2. This 25 reduces the speed of the motor 2 at a time which is one revolution of the cam shaft before the narrowing operation actually begins. This stays in during the narrowing but as soon as the lever 204 passes off of the lug 218, 30 the lever 206 will be moved into such position that the circuit will be closed through the contact 211 and the contact segment 213 thus energizing the magnet 215 to effect the closing of the switch 217. This cuts out the 35 resistance and the motor will now run its full speed during the straight knitting between the narrowings. The same operation takes place in the three different stages of narrowing such as, for example, the narrowing 40 220, during the making of the garter top, see Figure 43, during the narrowing 221 in the leg of the stocking and during the narrowing 222 during the making of the heel of the stocking. The narrowing operation is 45 accomplished in the usual manner of a full-fashioned hosiery machine and a detailed description is believed to be unnecessary, the construction for effecting the narrowing being shown more specifically in Figure 9.

50 It will be seen from Figure 9 that the foot pedal 193 is locked in position by means of the lever 194 to prevent its upward movement so that the link 195 is retaining the roller arm 196 and the narrowing shaft 197 in its upward position, the roller 198 being out of the

path of the cam 199, so that the narrowing mechanism may be locked in its inoperative position when desired. It will of course be understood that if desired the link 195 may be out of the path of the roller carrying arms 70 196 so that the narrowing mechanism is electrically controlled and timed.

In the knitting of a 1200 course stocking, the knitting of the garter top 186 takes place through 150 courses and the narrowing takes place through twenty courses. The welt is designated 185 in Figure 43 and after the welt is finished, it is turned over and knitted, as shown at line 186. After the garter top is finished, the machine stops at line 187 and the character of the stitches now changes from a loose to a tight stitch, as already explained. The last four courses of the cotton garter top are formed with a loose stitch so that the silk or other material which forms the leg 85 can be interstitched at such place. The leg 188 is then formed and in a 1200 course stocking has 540 courses. After 240 courses have been formed, the fashioning or narrowing automatically starts and continues for 90 140 courses in the manner already explained.

The manner in which the stitch is tightened or loosened has already been explained. The high splice 189 begins at line 190 and continues to line 191, see Figure 43. 95

During the knitting of the high splice the insulating member 112, see Figure 24, is beneath the brush 109 so that the circuit in line 104 is broken and the magnet 105 is deenergized to open the switch 106, see Figure 10, 100 which throws in a portion of the resistance 108 so that the speed of the motor is reduced during the knitting of the high splice. As soon as the insulating member 112 passes out of contact with the brush 109, the magnet 105 will be energized and the switch 106 will be closed so that the motor will operate at full speed. The circuit for this operation is through line 103, electro-magnet 105, line 104, brush 109, disc 110, disc 200, brush 201, line 203, line 97 to line 39 also line 35. The motor is now running at full speed and the formation of the heel begins at line 191. Just prior to this the loose courses 223 begin as the machine changes from silk to cotton. The narrowing 222 takes place during the formation of the heel, as already described. After the heel is finished the stockings thus far completed are removed from the machine and the foot and instep are formed on the usual machine. After the heel is finished, the machine begins the formation of the welts of the next lot of stockings. 115 120

125 It will of course be understood that while I have explained herein the automatic controlling and timing of a 1200 course stocking that I do not intend to be limited to the manufacture of stockings with this number of courses as the number of courses varies in accordance with the character of the ma- 130

terial used and the type of stocking which is to be manufactured and my novel timing and controlling mechanism may be employed to automatically control and time the manufacture of hosiery having any desired number of courses.

In accordance with my present invention, I employ controlling and timing mechanism for the different operations so that in each 10 operation a definite number of courses will be made which are not controlled by the operator but controlled automatically so that all of the stockings manufactured will be standard as to the number of courses in the 15 stocking. The same holds true as to the beginning and stopping of the narrowing and the length of the narrowing, the loose stitching, beginning and stopping of the high splice, as well as the length of the high 20 splice, and the lengths of the welt, garter top and heel.

It will be seen that in the timing mechanism employed, conducting discs or wheels and current carrying discs or wheels are employed which are arranged in sets and the 25 discs which form the timing discs are provided with insulating or conducting portions which can be so adjusted that at the desired time the circuit will be made or broken to accurately time the beginning and stopping of the different operations as well as the duration of each operation.

The resistance 108 is arranged in such a manner that taps can be taken at different 35 points so that the amount of resistance which is to be used may be varied as may be desired.

It will now be apparent that I have devised a new and useful automatic controlling 40 and timing mechanism for full-fashioned hosiery machines which embodies the features of advantage enumerated as desirable in the statement of the invention and the above description, and while I have, in the 45 present instance, shown and described embodiments thereof which will give in practice satisfactory and reliable results, it is to be understood that these embodiments are susceptible of modification in various particulars without departing from the spirit or 50 scope of the invention or sacrificing any of its advantages.

Having thus described my invention, what I claim as new and desire to secure by Letters Patent, is:—

1. The described mechanism for controlling knitting machines for producing full fashioned hosiery which comprises the combination with a knitting mechanism, of a narrowing mechanism, adapted to co-operate with the former, an electric motor, adapted to drive said knitting mechanism, a primary set of rotary electric circuit controlling means, connected with the knitting mechanism to be operated thereby, an electromag-

netic switch operatively connected with said electric motor and circuit controlling means, the latter being adapted to automatically control successive working periods of the knitting machine in accordance with the specific 70 number of courses to be made respectively in the welt, the garter top, the leg, the high splice and the heel section of the stocking, a second set of rotary electric circuit controlling means, connected with the knitting mechanism to be driven thereby, an electromagnetically operated pawl, operatively connected with said narrowing mechanism and the second set of circuit controlling means, the latter being adapted to automatically 75 control the narrowing mechanism in accordance with the designed shape of the stocking.

2. The described mechanism for controlling knitting machines for producing full fashioned hosiery which comprises in combination a knitting mechanism, a narrowing mechanism, adapted to co-operate with the former, a stitch adjusting mechanism, adapted to co-operate with the knitting mechanism, an electric motor, adapted to drive the knitting mechanism, a primary set of rotary electric circuit controlling means connected with the knitting mechanism to be driven thereby, an electromagnetic switch, operatively connected with said electric motor and circuit controlling means, the latter being adapted to automatically control successive working periods of the knitting machine in accordance with the specific number of courses to be made respectively in the welt, the garter top, the leg, the high splice and the heel section of the stocking, a second set of rotary electric circuit controlling means, connected with the knitting mechanism to be driven thereby, an electromagnetically operated pawl, operatively connected with said narrowing mechanism and the second set of circuit controlling means, the latter being adapted to control the narrowing mechanism 90 in accordance to the designed shape of the stocking, a third set of rotary circuit controlling means, connected with the knitting mechanism to be driven thereby, and an electromagnetically operated lever, operatively connected with the said stitch adjusting mechanism of the machine and said third set of circuit controlling means, and the latter being adapted to automatically control the stitch adjusting mechanism in accordance 95 with the designed structural characteristics 100 of the stocking.

3. The described mechanism for controlling knitting machines for producing full fashioned hosiery which comprises in combination a knitting mechanism, a narrowing mechanism, adapted to co-operate with the former, a stitch adjusting mechanism, adapted to co-operate with the knitting mechanism, an electric motor, adapted to drive the knitting mechanism, a primary set of rotary elec- 110 115 120 125 130

tric circuit controlling means connected with the knitting mechanism to be driven thereby, an electromagnetic switch, operatively connected with said electric motor and circuit controlling means, the latter being adapted to automatically control successive working periods of the knitting machine in accordance to the specific number of courses to be made respectively in the welt, the garter top, the 10 leg, the high splice and the heel section of the stocking, a second set of rotary electric circuit controlling means, connected with the knitting mechanism to be driven thereby, an electromagnetically operated pawl, operatively connected with said narrowing mechanism and the second set of circuit controlling means, the latter being adapted to control the narrowing mechanism in accordance with the designed shape of the stockings, a

third set of rotary circuit controlling means, 20 connected with the knitting mechanism to be driven thereby, and an electromagnetically operated lever, operatively connected with the said stitch adjusting mechanism of the machine and said third set of circuit controlling means, and the latter being adapted to automatically control the stitch adjusting mechanism in accordance with the designed structural characteristics of the stocking, a pattern chain presenting contact lugs and 25 being operatively connected with the narrowing mechanism and, an electric speed regulating apparatus, operatively connected with the electric motor and said pattern chain, the latter being adapted to automatically control 30 the speed of the electric motor in timed relation to the narrowing operations.

JAMES E. SHOEMAKER.
